UNITED STATES PATENT OFFICE.

ARTHUR WILLIAM ZIEGLER, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

CURRENT-BALLASTING DEVICE.

Application filed October 5, 1925. Serial No. 60,476.

This invention relates to current ballasting devices and has particular application to the type employing an iron wire resistance element.

5 It has for an object to provide a current ballasting device which is easily constructed, possesses long life and operates efficiently over a wide range of voltages.

In the operation of a plurality of vacuum 10 tubes it is usually customary to employ a single source of potential to supply heating current to all the filaments of said tubes. In many cases in such operations, it is desirable to regulate the heating current supplied very 15 closely and current ballasting devices may then be connected in series with a source of potential for this purpose. One type of current ballasting or regulating device which has been heretofore employed is the iron wire 20 ballast lamp comprising an iron wire resistance mounted in a chamber containing an inert gas, such as hydrogen. A discussion of the theory and uses of such a ballasting device may be had from an article by H. A. 25 Jones in the General Electric Review for May, 1925 page 329.

Such devices, however, have a limited voltage range of effective or efficient operation and when operating over their maximum 30 effective range require greater care in their manufacture than is suited for economical commercial production. Furthermore, the life of this type of ballast device has been found to depend substantially upon the temperature at which it operates or upon the voltage impressed upon it, and decreases rapidly as the operating voltage approaches the maximum effective voltage.

A feature of the invention comprises a ballast lamp of the iron wire resistance type having two or more filaments adapted to be connected in series and shunts for normally shunting a predetermined number of said filaments and means for opening the shunt 45 across one of said filaments when the voltage impressed upon the device exceeds the effective voltage of the filament in operation. Such a device may be connected for example in series with the source of heating currents 50 for vacuum tube filaments to regulate the filament current within narrow limits over a wide range of voltages.

Another feature of the invention is the use

of a plurality of single filament lamps in place of multiple filaments in a single lamp 55 as described above.

A fuller understanding of the invention will be had from the more detailed description to be given in connection with the accompanying drawings in which the same reference characters represent similar parts.

Fig. 1 shows a ballasting device comprising a multiple filament ballast lamp in accordance with one feature of the invention connected so as to regulate the filament current of a plurality of vacuum tubes connected in tandem.

Fig. 2 shows the manner in which the plurality of single filament ballast lamps may be connected to operate in place of the multiple filament lamp of Fig. 1.

Referring to Fig. 1 of the drawings, a plurality of vacuum tubes 1 comprising anodes 2, control electrodes 3, cathodes 4 are shown connected in tandem as is well understood in the art. Heating current is supplied to the 75 cathodes 4 from a source of potential 5, through a retard coil 6, a suitable fuse 7 and a current ballasting device. The retard coil 6 operates to eliminate noises by offsetting sudden fluctuations in the battery current. In 80 accordance with the invention, the ballasting device may comprise a ballast lamp 8 having filaments 9 and 10 adapted to be connected in series in the filament heating circuit and a high-resistance marginal relay 11 and a shunt 85 12 normally placed across one filament, 10 for example. Relay 11 is designed to operate when the potential across the circuit exceeds the effective operating voltage of filament 9. When relay 11 operates it opens shunt 12 90 thereby connecting filaments 9 and 10 in series.

When a multiple filament ballast lamp as described above is employed for the primary purpose of regulating the filament current 95 within extremely narrow limits, the first filament as filament 9 is preferably made longer than the second filament as filament 10 so that the change in the ballasting filament temperature resulting when relay 11 operates is 100 not such as to cause an appreciable change in the ballasted current.

Furthermore, it is known that the life of a ballast lamp filament is dependent primarily upon the temperature or voltage at which it 105 operates and that the life is greatly shortened

as the operating voltage approaches or exceeds the maximum of the effective range. In the arrangement according to this invention, therefore, the life is substantially increased 5 and the tendency for the characteristics for a lamp to change decreased, since the filaments operate at temperatures or voltages appreciably below their individual effective maxima.

- 10 In the arrangement of Fig. 2 a plurality of single filament ballast lamps 13 and 14 are substituted for the multiple filament lamp 8. As in the first arrangement, a relay 11 is employed to place the lamps 13 and 14 in series 15 when the applied potential difference exceeds the effective voltage of lamp 13 by attracting its armature 12, which in its unattracted position shunts lamp 14.

The filaments of the multiple filament lamp 20 or of the single filament lamps are composed of some metal having a positive temperature coefficient such as pure iron wire and are mounted in a chamber containing an inert atmosphere such as hydrogen. A suitable 25 lamp for use over a voltage range of from 2 to 9 volts might be, for example, two filaments of pure iron wire approximately six centimeters long and .0096 centimeters in diameter, in an atmosphere of hydrogen under 30 a pressure of 20 millimeters of mercury. As an example of a satisfactory lamp for use when it is desired to maintain current within extremely narrow limits, a lamp having its first filament 6 centimeters long and a second 35 filament 3.8 centimeters long, both filaments being approximately .0096 centimeters in diameter in an atmosphere of hydrogen under a pressure of 15 millimeters of mercury may be used.

- 40 It will be evident that other suitable contact making devices, such as contact making voltmeters, may be substituted satisfactorily for the marginal relay shown herein.

It is also evident that the methods of ballasting currents in accordance with the invention may be modified to include the use of more than two filaments in a single lamp or the use of any number of ballast lamps containing single filaments. Similarly, the relay or relays operating the shunt or shunts 50 may be placed in any part of the circuit where it may seem desirable; in some cases, therefore, a single relay or contact making device with a multiplicity of contacts may be preferable where more than two filaments or single filament ballast lamps are employed.

- The arrangements of the present invention have been found to be particularly adapted 60 for use for current regulation within narrow limits over a wide range of voltage as desired. Tests have shown, for example, that the device represented in Fig. 1 may be employed to maintain the current within a variation of 10% over a voltage variation greater than 65 800%; further, if only the most efficient op-

erating range of the device was considered, the current was found to be maintained with 1.7% over a potential change of 250%.

While the invention has been described herein with reference to a particular type of regulating device and to a particular type of circuit to be regulated, it will be understood that it is not intended to limit the invention to these applications alone, but that all features of the invention are susceptible of various adaptations and modifications within the scope of the appended claims.

The term "effective voltage" is employed herein to define any voltage within the range of applied voltages over which the device will 80 maintain the ballasted current substantially constant.

What is claimed is:

1. In combination, an electrical circuit, a source of potential for said circuit, a plurality of ballasting elements adapted to be connected in series in said circuit, one of said elements being normally connected in said circuit, means for increasing the range of effective ballasting, said means comprising 85 means connected in parallel with said one element and acting in response to voltage changes in said circuit for connecting another of said elements in series with said one element when the voltage across said circuit exceeds the effective ballasting range of the said 90 one element.

2. In combination, an electrical circuit, a source of potential for said circuit, a ballasting arrangement, said arrangement comprising 100 a plurality of ballasting elements adapted to be connected in series in said circuit, each of said elements having a positive temperature coefficient, and one of said elements being normally connected in said circuit, means for increasing the range of effective ballasting of 105 said arrangement, said means comprising means connected in parallel with said one element and acting in response to voltage changes in said circuit for successively connecting additional of said elements in series 110 with said one element when the voltage across said circuit exceeds the effective ballasting voltage of the ballasting means already in 115 said circuit.

3. In combination, an electrical circuit, a source of potential for said circuit, an iron wire ballasting element comprising a plurality of iron wire filaments adapted to be connected in series with said source, one of said 120 filaments being normally connected in said circuit, means connected in parallel with said one filament and acting in response to voltage changes in said circuit for connecting another of said filaments in series with said circuit 125 when the voltage across said circuit exceeds the effective ballasting voltage of the said one filament.

4. In combination, a plurality of electron discharge devices, each of said devices hav- 130

ing an anode and a cathode, a source of potential for supplying heating current to said cathodes, a ballasting arrangement for regulating said heating current over a wide range of voltages, said arrangement comprising a plurality of iron-wire resistance ballasting elements adapted to be connected in series, one of said elements being normally connected in series with said source, and means for increasing the range of effective ballasting

of said arrangement, said means connected in parallel with said one element and acting in response to voltage changes in said source for bringing additional of said elements into serious relation with said source when the voltage across said source exceeds the effective ballasting voltage of said one element. 15

In witness whereof, I hereunto subscribe my name this 3rd day of October, A. D. 1925.

ARTHUR W. ZIEGLER.
